UNITED STATES PATENT OFFICE

RAYMOND W. COOK, OF BRISTOL, CONNECTICUT, ASSIGNOR TO THE WALLACE BARNES COMPANY, OF BRISTOL, CONNECTICUT, A CORPORATION

CLIP

Application filed September 9, 1930. Serial No. 480,686.

This invention relates to an improved clip, primarily intended for use in fastening business papers, etc., together, but available for use in a wide variety of situations.

The main object of this invention is to produce a convenient, effective and capacious clip, having provision for the display of advertising matter, etc., and constructed with particular reference to reliability and low cost for manufacture.

With the above and other objects in view as will appear from the following, my invention consists in a clip made of resilient sheet metal and consisting of a face-plate 15 having an integral resilient shank originating at the edge thereof and bent reversely to extend behind the same; and an integral gripping-arm originating at another point upon the edge of the said face-plate and bent reversely therefrom to extend between the same and the said shank and co-operating with the latter to provide yielding gripping-means.

My invention further consists in a clip characterized as above and having certain other details of construction as will be hereinafter described and particularly recited in the claims.

In the accompanying drawings:

Fig. 1 is a view in front elevation of one form which a clip embodying my invention may assume;

Fig. 2 is an edge view thereof;

Fig. 3 is a view thereof in vertical central section taken on the line 3—3 of Fig. 1;

Fig. 4 is a corresponding view but showing the clip applied to a relatively-thick piece of fabric;

Fig. 5 is a face view of a partly-formed blank from which the clip shown in the preceding figures is made; and

Fig. 6 is an edge view thereof.

The particular clip chosen herein for the illustration of my invention consists of a face-plate 10, preferably circular and of concavo-convex form, as shown, and designed to have directly imprinted upon its front face such advertising or other matter as may be desired, or if preferred, a secondary plate 50 of celluloid or other suitable material may

bear the advertising matter and in turn be secured to the face-plate in accordance with the well-known practice in the art.

Connected to the upper edge of the face-plate 10, by means of a bowed reach 11, and extending downward behind the same, is an integral flexible shank 12, the lower end of which extends as shown well below the lower edge of the said face-plate. The shank 12, just referred to, has struck forwardly from its longitudinal center an integral gripping-finger 13 having its upper end 14 bowed rearwardly to prevent the cutting of the papers or other material when the clip is removed therefrom.

The gripping-finger 13 of the shank 12 is adapted to lie between and to act in conjunction with a pair of complementary spaced-apart gripping-fingers 15 and 16 to yieldingly grip the object upon which the clip may be mounted. The said gripping-fingers 15 and 16 have their respective upper ends 17 and 18 bowed forwardly and constitute the bifurcated upper end of a resilient gripping-arm 19 bent upwardly from the lower edge of the face-plate 10 and extending between the rear face of the same and the front face of the shank 12.

The lower end of the gripping-arm 19 is sharply bent reversely and slopes slightly forward, as shown, to provide a guide-lip 20 to facilitate the entry of the article upon which it is desired to mount the clip between the rear face of the gripping-arm 19 and the forward face of the shank 12.

As shown in Fig. 4, the clip is applied to the edge of a piece of fabric 21 and it will be noted that the latter is gripped between the forward face of the gripping-finger 13 of the shank 12 and the rear faces of the complementary spaced-apart gripping-fingers 17 and 18 of the gripping-arm 19, so as to be slightly deflected into the space between the two latter fingers to increase the grip. The fabric 21 is also gripped between the forward face of the shank 12 and the rear face of the said gripping-arm 19 near the lower edge thereof adjacent the guide-lip 20, already referred to.

By forming the shank 12 and the gripping-

arm 19 integral with the face-plate 10 and folding them from different points upon the edge of the said plate so as to bring them into co-operative relationship for gripping an article, the resultant clip is not only more effective and durable, but it enables the said face-plate 10 to be left imperforate so that, if desired, advertising matter, etc., may be applied thereto by printing or by decalcomania, etc., or by applying celluloid or a thin plate over the face thereof in accordance with the well-known practice in the art to which my invention relates. Furthermore, the resiliency obtained by the relatively-long gripping-arm 19 in conjunction with the shank 12 provides a secure gripping for a wide range of thicknesses of material.

I claim:

1. As a new article of manufacture, a clip made of resilient sheet metal and consisting of a face-plate having an integral shank originating at the edge thereof and bent reversely to extend behind the same; and an integral gripping-arm originating at another point on the edge of the said face-plate and bent reversely therefrom to extend between the same and the said shank and co-operating with the latter to provide yielding gripping-means, the said arm being pinched upon itself at such bend to form a forwardly-inclined guide-lip and finger-piece.

2. A clip as defined in claim 1 and having the shank and gripping-arm respectively bent from opposite edges of the face-plate and cut to form gripping-members crossing each other in the space between the face-plate and the body of the shank.

3. As a new article of manufacture, a clip made of resilient sheet metal and consisting of a substantially-circular face-plate having an integral shank originating at the edge thereof and bent reversely to extend behind the same; and an integral gripping-arm originating on the edge of the said face-plate at a point diametrically opposite the point of origin of the said shank and bent reversely from the said face-plate to extend between the same and the said shank and co-operating with the latter to provide yielding gripping-means, the said arm being pinched upon itself at its bend to form a forwardly-projecting guide-lip and finger-piece and the said shank and arm being cut to form yielding-fingers arranged to cross each other in the space between the face-plate and the body of the said shank.

4. As a new article of manufacture, a clip made of resilient sheet metal and consisting of a face-plate having an integral shank originating at the edge thereof and bent reversely to extend behind the same; and an integral gripping-arm originating at another point on the edge of the said face-plate and bent reversely therefrom and pinched upon itself to form a forwardly-inclined guide-

lip and extending between the said face-plate and the said shank to co-operate with the latter to provide yielding gripping-means.

5. As a new article of manufacture, a clip made of resilient sheet metal and consisting of a substantially-circular face-plate having an integral shank originating on the edge thereof and bent reversely to extend behind the same; and an integral gripping-arm originating on the edge of the said face-plate at a point diametrically opposite the point of origin of the said shank and bent reversely from the said face-plate and pinched upon itself to form a forwardly-inclined guide-lip and extending between the said face-plate and the said shank to co-operate with the latter to provide yielding gripping-means.

6. As a new article of manufacture, a clip made of resilient sheet metal and consisting of a face-plate having an integral shank originating at the edge thereof and bent reversely to extend behind the same; an integral gripping-arm originating at another point on the edge of the said face-plate and bent reversely therefrom to extend between the same and the said shank; and an integral gripping-finger respectively formed upon the said shank and the said gripping-arm and positioned to cross each other to provide yielding gripping-means.

7. As a new article of manufacture, a clip made of resilient sheet metal and consisting of a face-plate having an integral shank originating at the edge thereof and bent reversely to extend behind the same, and pinched upon itself at such bend to form a guide-lip and finger-piece; and an integral gripping-arm originating at another point on the edge of the said face-plate and bent reversely therefrom to extend between the same and the said shank, the said shank and gripping-arm being provided with co-operating gripping-fingers, one with a pair of spaced-apart fingers and the other with a finger registering with the space between the two said spaced-apart fingers, and the said fingers being bent to cross each other.

8. As a new article of manufacture, a clip made of resilient sheet metal and consisting of a face-plate having an integral shank originating at the edge thereof and bent reversely to extend behind the same; and an integral gripping-arm originating at another point on the edge of the said face-plate and bent reversely therefrom and pinched upon itself to form a forwardly-inclined guide-lip and extending between the said face-plate and the said arm and having its free end bifurcated to form a pair of gripping-fingers for co-operation with the said shank to provide yielding gripping-means.

In testimony whereof, I have signed this specification.

RAYMOND W. COOK.
